[57] CLAIM

The ornamental design for the pouch containing liquid
soap or the like for use with a dispenser unit, as shown
and described.

DESCRIPTION

FIG. 1 is a front elevational view of a pouch containing liquid
soap or the like for use with a dispenser unit showing my new design, the rear being plain and unornamented; and

FIG. 2 is a right side elevational view thereof, the left
side being a mirror image of that shown.
